RESPIRATOR

Franklin O. Church, Buffalo, N. Y., assignor to
Dunlop Tire and Rubber Corporation, Buffalo,
N. Y., a corporation of New York

Application February 25, 1942, Serial No. 432,174

4 Claims. (Cl. 128—30)

My invention relates to a respirator for producing artificial respiration, of the type in which a partial vacuum is applied to the chest and abdominal parts of the user's body to cause inspiration followed by a period of admission of air to the surface of the body to cause expiration.

More particularly, my present invention applies to respirators in which a covering is applied over the chest and abdominal parts of the body and sealed to the body by a supporting wall of cellular material, such as foamed latex rubber, substantially sealed against the inflow of air.

Heretofore respirators of the above type have been made of a stiff molded material which is correspondingly cumbersome and expensive. In my present invention I provide a respirator that has sufficient rigidity to retain its position against the pressure exerted upon it under partial vacuum and which is light in weight, simple in construction and readily applicable to the body.

In my present invention I provide a wall or shield of a curvature approximating that of the body of the user and sufficient to cover the body from approximately the neck to the abdomen and to extend below the arms and around the sides of the user to overlap the back to a small extent so that it may be held firmly in position.

This shield is spaced from the body of the user by a marginal wall of cellular resilient material, such as foamed latex rubber, the outer surface of which has been rendered substantially impermeable to the passage of air by means of a coating or layer of rubber cement or latex.

The shield is made of layers of rubberized fabric in which are embedded longitudinal rods or strips of a stiff material, such as metal, and transverse strips of spring material extending across the front of the shield and around the sides of the user and sufficiently resilient that it may be opened slightly to pass about the body of the user and to cling thereto when released.

The various features of the invention are illustrated, by way of example, in the accompanying drawing in which

Fig. 1 is a perspective view showing the respirator as applied to the body of the user;

Figs. 2, 3 and 4 are respectively, front, side and rear views of the respirator, and

Figs. 5 and 6 are sections taken respectively on the lines 5—5 and 6—6 of Fig. 2.

In the respirator illustrated in the accompanying drawing, a shield is made up of one or more layers of rubberized fabric 10 of a suitable shape. Preferably two or more layers of rubberized fabric are superposed and pressed and

vulcanized together. This provides a light material that is sufficiently airtight to form the shield. This material is given the desired shape and sufficient rigidity in a lengthwise direction by means of rods 11, 12 and 13, three rods being shown by way of example, which extend from approximately the top edge of the fabric to the lower edge thereof and are secured to the fabric or embedded therein by means of lengthwise strips 14, 15 and 16, which may be attached to the strips 10 in any suitable manner as, for example, by being lapped under the fabric and secured thereto prior to vulcanization.

The strips 14, 15 and 16 may be of the same rubberized material as the fabric 10.

The rods 11, 12 and 13 and their strips may be attached either to the inside or outside of the shield. The shield is given rigidity in the opposite direction and is given a rounded shape by means of curved spring bands 17 and 18 extending horizontally or transversely over the front and sides and slightly curving in at the back so that when in place on the body of the user, to whom artificial respiration is to be applied, the compressing action of the spring holds the respirator gently in position.

The respirator may be readily applied by merely pulling the side edges of the shield outwardly, as indicated in broken lines in Fig. 6, placing it in position on the wearer and then permitting the edges to return to their normal positions.

The springs 17 and 18 are secured to the shield by being embedded therein as, for example, by applying strips of rubberized fabric 19 and 20 over the springs 17 and 18 and securing them to the surface of the rubberized fabric of the shield by vulcanization, or by cementing and vulcanization.

It will be understood that these springs may be placed either on the inner or outer surface of the shield.

The shield is supported at a small distance from the body of the user to form a vacuum chamber immediately above the chest and abdomen by means of a marginal wall 21 of foamed latex rubber. The outer surface, as for example at 22 in Figs. 2 and 3, is sealed by the application of a layer of cement or latex to the foamed latex rubber thus forming an impervious outer coating to approximately the inner edge of the wall and sealing the vacuum chamber against the inflow of air, except for an insignificant margin next to the user's skin.

Foamed latex rubber has the advantage that it can be kept adjacent the skin of the wearer an

indefinite period of time without causing irritation or forming sores. This is largely due to the fact that air may penetrate it without obstruction.

The ends of the rods 11, 12 and 13 and of the springs 17 and 18 overlap and rest on the annular cellular wall. The pressure of the ends of the rods is distributed sidewise by the ply or plies of rubberized fabric thereby avoiding a localized area of pressure on the cellular structure.

Connection to a suitable pump and control apparatus may be made through a connecting pipe 23 secured in the fabric 10 in any suitable manner.

The above construction has the advantage that it is very light in weight and inexpensive to construct, while having all of the properties required to sustain atmospheric pressure during application of the vacuum and yet remaining accurately in position on the user's body.

While preferably applied immediately against the skin, it may be quickly adjusted onto a clothed person's body in cases of emergency. Because of its lightness in weight and the ease with which it can be applied it is well adapted for emergency cases, such as drowning, industrial accidents, shock, or when respiration ceases during surgical operations.

The shield 10 may be built in any suitable manner preferably a fabric shell is built up, ply by ply, of vulcanizable rubberized fabric on a shaped metal former. The reinforcing rods are bent to fit the shape of the former and assembled to the plies and transverse spring steel bands are also shaped and attached to the unvulcanized plies while still on the former. The assembly is then vulcanized and it retains the shape given it by the former. The plies of vulcanized rubber have the required shape because of being vulcanized in that shape independently of the rods 11, 12 and 13 and the spring bands 17 and 18. The rods and the springs, however, aid in holding the fabric in shape against outside pressure.

What I claim is:

1. A respirator which comprises a wall of cellular rubber to enclose a body area and substantially sealed against passage of air, a shield resting on said wall to cover said area and comprising rubberized fabric, spaced rods secured to said fabric and extending longitudinally of said shield and a transverse spring band secured to said shield and curved to extend about the front and sides of the body to the back.
- 5 2. A respirator which comprises a wall of cellular rubber to enclose a body area and substantially sealed against passage of air, a shield resting on said wall to cover said area and comprising rubberized fabric, spaced longitudinal reinforcements for said fabric and transverse spring reinforcements for said fabric to cause said respirator to engage the sides of a body.
- 15 3. A respirator which comprises a wall of resilient material shaped to enclose the chest, abdomen and sides of a body, a covering shield overlying said wall and the area enclosed thereby and comprising rubberized fabric having longitudinal reinforcements extending over and supported by said wall and a transverse spring band extending in a transverse direction across the front and side portions of said shield to press said respirator on the body.
- 20 4. A respirator comprising a resilient enclosing wall shaped to enclose the chest, abdomen and parts of the sides of the body, a flexible resilient covering shield extending over said wall and the area enclosed thereby and sealed to said wall, reinforcements extending longitudinally of said resilient covering material and spring means extending transversely of said material and curved to cause said respirator to engage the sides of a body to which said respirator may be applied and secure it firmly thereon.
